UNITED STATES PATENT OFFICE.

ALBERT COLLET, OF PARIS, FRANCE.

PORTABLE INSULATED SUPPORT FOR DOUBLE-WIRE ELECTRIC LINES.

No. 816,900.

Specification of Letters Patent.

Patented April 3, 1906.

Application filed May 19, 1904. Serial No. 208,781.

To all whom it may concern:

Be it known that I, ALBERT COLLET, a citizen of the Republic of France, residing in Paris, France, have invented certain new and useful Improvements in Portable Supports for Double-Wire Electric Lines, of which the following is a specification.

This invention relates to supports for electric conductors—such, for example, as the double wires employed for lighting, transmitting power, and the like; and the object is to provide a portable ladder-like insulated support for the two wires, all as will be hereinafter described.

15 The novel features of the invention will be carefully defined in the claims.

In the accompanying drawings, which illustrate an embodiment of the invention, Figures 1 and 2 are respectively a side and front elevation of the support on a relatively small scale. Figs. 3 and 4 are similar views, respectively, to Figs. 1 and 2 of the upper part only of the support on a much larger scale than that of Figs. 1 and 2. In Fig. 4 the parts are in section at the left-hand side. Fig. 5 is a sectional plan on the broken line M N O. Fig. 6 is a cross-section of the locking device of the winch-frame at line P Q in Fig. 3. Figs. 7 and 8 are detail views of the lever *m* and its pawl, the former being a face view and the latter an edge view.

The support consists in a general way of two wooden ladders hinged together at their tops to form when in use an A-shaped frame, Fig. 1, these ladders being held in their divergent positions by tie-bars below carrying a drum for wire and above by winch-frames carrying winches for straining the steel suspending-cables. There is a hood at the top 35 for protecting the parts and for housing incandescent lamps. The wooden ladders *a* and *b* are or may be alike, and being of wood they serve to insulate the line-wires from the earth. Mounted slidably in metal end pieces 40 on each ladder is a foot or base bar *c*, which rests on the ground. In Fig. 2 the dotted lines indicate how this bar may be moved more or less to one side or the other as occasion may require to get the best support. 45 The ladders *a* and *b* are provided at their respective upper ends with metal hinging-pieces *d* and *e*, connected by hinging journals or pins *f* with heads *y*, embraced between wooden blocks *g*, secured by bolts and nuts *z*, 50 as clearly shown in Fig. 4. The blocks *g* form an insulating-frame between the metal

parts *d e* at each side. The pins *f* serve also as journals, respectively, for sheaves *h*, over which pass flexible steel cables *a'* and *a''*, which extend down, respectively, to winches *k*, which will now be described. The winch comprises a drum secured by a screw *d'*, Fig. 5, on a tubular shaft *n'*, rotatively mounted in a swinging frame *l*, which has hinging-eyes that turn on the cylindrical socket portion of the metal hinge-pieces *d*, being held against sliding up and down thereon by an upper collar *b'*, secured by a pin *b'*, and a lower clamping-collar *b''*. At its free end the frame *l* has a hook *r*, which takes about the cylindrical 60 socket portion of the hinge-pièce *e* between collars *b'* and *b''*, like those before described. When the hook *r* is engaged, as in Figs. 3 and 5, it is held against disengagement by a locking device which turns on the hinge-pièce *e* 65 between the collars *b'* and *b''*. This device comprises two rings *p* and a tie-bar *q*, which when moved around to the position seen in full lines in Fig. 5 locks the hook in position; but when moved to the position seen in dotted lines at *q'* releases the hook and allows the winch-frame to be swung around, so that the ladders *a b* may be folded in together. To operate the winch, there is a ratchet-wheel *n* fixed on the end of the tubular shaft 70 *n'*, and on the frame *l* is mounted a stop-pawl *o*, which engages the ratchet-wheel. An operating-lever *m* has on its end, Figs. 7 and 8, a pin *f'*, which enters and turns in the hollow shaft *n'* as a bearing, and said lever carries a 75 pawl *o'* to engage the ratchet-wheel *n*, said pawl having a spring *q'*, which holds it up to the ratchet-wheel when the lever is in place and up to a stop *r'* when the lever is disengaged. This lever is for the purpose of rotating the winch so as to put a strain on the cable. At their lower part (see Figs. 1 and 2) the ladders are connected by a tie bar or frame *s*, hinged to the ladder *b* and hooking at its free end on a rung of the ladder *a*. This 80 frame has mounted in it a drum or reel *t* for wire.

The conductor *a'*, Figs. 1 and 3, is provided at its end with a chape *c'*, which engages a hook *i*, coupled by a link *j* with the pin *f*. 85 The flexible conductors *u*, Fig. 1, provided with pins at their ends, electrically connect the various sections of the line on either side of the supports.

Mounted in the blocks *g* is an upright 90 stem, and on this stem is mounted a hood *v* to protect the parts from rain and to house

incandescent lamps *w*. On the lower end of the stem is a ring or eye *x*, to which may be secured a guy for bracing the support.

It will be noted that each ladder or ladder-like member of the support comprises two uprights and connecting-rungs, and that while the ladder as a whole has means for insulating from the ground the parts it carries at its top means are also provided for insulating the parts carried at one side of the support from those carried at the other side—that is to say, the sheave *h* and winch *k* at one side are insulated from those at the other side.

15 As only one support is shown, it may be well to explain that the cable or steel-wire rope used for straining the wire is connected at one end to the wire and that the other end of the wire is connected through the chape *c'* 20 to the hook *i*. The wires at the opposite sides of the support are connected electrically by the conductor *u*.

Having thus described my invention, I claim—

25 1. A portable support for electric conduc-

tors, consisting of two ladders hinged together at their upper ends, said ladders being provided with means for insulating them from the ground and means for insulating the uprights at one side from those at the other 30 side, and winches for straining the wires mounted on the respective sides of the support.

2. A portable support for electric wires, having two upright members hinged together 35 at their upper ends, a sheave, a winch-frame hinged about one of the members and provided with a hook to engage the other member, a locking device for said hook hinged on the last-named member, a winch-drum 40 mounted in said frame, and means for rotating said drum.

In witness whereof I have hereunto signed my name in the presence of two subscribing witnesses.

ALBERT COLLET.
